UNITED STATES PATENT OFFICE.

FREDERICK W. MOFFAT, OF WESTON, ONTARIO, CANADA.

SUPPORT FOR RESISTANCE WIRING.

Application filed January 19, 1924. Serial No. 687,231.

To all whom it may concern:

Be it known that I, FREDERICK W. MOFFAT, of the town of Weston, in the county of York, Province of Ontario, Canada, a subject of the King of Great Britain, have invented certain new and useful Improvements in Supports for Resistance Wiring, of which the following is a specification.

This invention relates to devices for supporting coiled resistance wiring and more particularly to supports adapted to permit free radiation. Heretofore it has been common practice to support coiled resistance wiring at a number of points intermediate 10 the ends of the coil. This arrangement permits the coil to sag intermediate its supports and make a short circuit. In my United States Patent No. 1,413,678, dated the 25th day of April, 1922, I show means for externally engaging the coiled resistance wiring to reduce the length of span between the supports but these means are inadequate in large ovens and furnaces where very high temperatures are attained. The object of 20 my present invention is to provide a resistance support which will overcome the above objectionable features, that will permit free radiation and that will leave a sufficient length of the resistance wiring entirely exposed between its external supports.

I attain my objects by means of the constructions hereinafter described and illustrated in the accompanying drawings in which—

Fig. 1 is a side elevation of my improved support with supporting cores shown in position in a coiled resistance which is externally supported in supporting bars, one of the latter being shown in end elevation while 30 two are shown in section;

Fig. 2 a cross section on the line 2—2 in Fig. 1 showing a supporting bar and a portion of an adjacent bar in side elevation, a portion of a bar being shown in vertical 40 section to show the end elevation of my improved support;

Fig. 3 a perspective view of my improved internal support; and

Fig. 4 a side elevation of a modified form 50 of support.

In the drawings like numerals of reference indicate corresponding parts in the different figures.

The supports 1 are formed of bars of any 55 insulating material and are suitably arranged within an oven or a furnace to carry

the heating element 2. The latter is helically coiled and strung on the supporting bars as follows. Each support is provided with a plurality of transverse bearings 3 and each bearing is provided with a plurality of spaced shoulders 4. These shoulders extend longitudinally of the axis of the helical heating element 2 and are extended laterally from each side of the bar 1. The 60 coils of the element are externally engaged by the shoulders. The spaces between the latter thus permit free radiation from the heating element.

It is obvious that the coils of the element, 70 when carried horizontally, tend to sag intermediate their supports, particularly when heated to a high temperature. This sometimes caused short circuits or the breakage of the coils and the above mentioned spaced 75 shoulders were provided to overcome this objectionable feature. This construction forms the subject matter of the hereinbefore mentioned patent and accomplishes its purpose when used for supporting small heating elements such as used in ovens for domestic stoves and the like.

In large ovens or furnaces using very large elements attaining very high temperatures the shoulders 4 do not provide sufficient support for the coiled elements. To overcome this I provide cores or internal supports 5, of insulating material, which extend axially through the helical heating element. These internal supports extend substantially from one external support to another external support. The preferable arrangement is to extend each internal support from the center of one external support to the center of the adjacent external support so that the internal supports break joint with the external supports. To permit free radiation of the heating element the cross sections of the cores 5 are so shaped as to prevent their full surfaces engaging 90 the inner sides of the helical element. In other words it is desirable to provide longitudinal grooves 6 between the helices and the core. This is accomplished by forming longitudinally spaced ribs 7 on each core, 95 these ribs being adapted to only engage the inner sides of the helices on longitudinal lines of very small surface areas.

With this construction the spans of coiled 110 heating element between the adjacent external supports 1 are supported by the internal supports 5. This is clearly illus-

trated in Fig. 1 in which one internal support is omitted to indicate the average sag of an unsupported span of heating element. The internal supports or cores thus entirely eliminate the strain on the heating element while the efficiency of the latter is not reduced.

As shown in Fig. 4 a helically ribbed support may be employed for the straight ribbed support shown in the other views.

What I claim is:—

1. The combination with a horizontally arranged helical electric heating element, and a plurality of external supports for said element, of an internal support extending axially through the element.

2. The combination with a horizontally arranged helical electric heating element, of a plurality of external supports for said element, of an internal support extending axially through the element and provided with spaced ribs adapted to engage the inner sides of the helices of the element.

3. The combination with a horizontally arranged helical electric heating element, and a plurality of supports for said element, each support having a plurality of spaced shoulders for externally engaging the helices of the element, of an internal support extending axially through the element.

4. The combination with a horizontally arranged helical electric heating element, and a plurality of supports for said element, each support having a plurality of spaced shoulders for externally engaging the helices of the element, of an internal support extending axially through the element.

and provided with spaced ribs adapted to engage the inner sides of the helices of the element.

5. The combination with a horizontally arranged helical electric heating element, and a plurality of external supports for said element, of an internal support for the element extending substantially from one external support to another.

6. The combination with a horizontally arranged helical electric heating element, and a plurality of external supports for said element, of an internal support extending axially through the element and provided with spaced ribs adapted to engage the inner sides of the helices, the internal support extending substantially from one external support to another.

7. The combination with a horizontally arranged helical electric heating element, and a plurality of supports for said element, each support having a plurality of spaced shoulders for externally engaging the helices of the element, of an internal support for the element extending substantially from one external support to another.

8. The combination with a horizontally arranged helical electric heating element, and a plurality of external supports for said element, of a plurality of internal supports extending axially through the element, the internal supports being adapted to break joint with the external supports.

Signed at Toronto, Canada, this 10th day of January, 1924.

FREDERICK W. MOFFAT.
